UNITED STATES PATENT OFFICE.

GEORGE E. VAN DUSEN, OF CLEVELAND, OHIO.

SMOKER'S UTENSIL.

1,200,551.

Specification of Letters Patent. Patented Oct. 10, 1916.

Application filed August 23, 1915. Serial No. 46,783.

To all whom it may concern:

Be it known that I, GEORGE E. VAN DUSEN, a citizen of the United States, residing at Cleveland, in the county of Cuyahoga and State of Ohio, have invented new and useful Improvements in Smokers' Utensils, of which the following is a specification.

This invention relates to smokers' utensils, and the object thereof is to produce a comparatively inexpensive match box holder having simple and efficient means for cutting off the tip of a cigar and also for holding and shielding a lighted match from the wind, the device being so constructed that it conforms snugly to the size and shape of the standard types of pocket boxes of safety matches.

With the foregoing and other objects in view, my invention consists in the details of construction and in the arrangement and combination of parts to be hereinafter more fully set forth and claimed.

In describing the invention, reference will be had to the accompanying drawings, wherein like characters denote corresponding parts in the several views, and in which—

Figure 1 illustrates a front perspective view showing the device holding a box of matches and also holding and shielding a burning match from the wind. Fig. 2 is a perspective view from the side and rear showing the match box inclosed for convenient carriage in the pocket. Fig. 3 is a view in perspective of the underneath part of the top end on the line X—X of Fig. 1.

In an application filed July 6, 1914, Serial No. 849,062 (which application has been allowed), I described and claimed a holder having an open side in communication with an open bottom end and a partially open top end, as in the present general construction. In that invention, however, a projecting hood was employed on the top end to house the cutting knife and also to provide a notch for holding a match stem. In the present construction the projecting hood is entirely eliminated, the whole device being made to conform snugly to the match box; and the whole device, excepting the cutting knife, being preferably made from a single sheet of material which has portions of one of its ends so fashioned and prepared that, when secured in position, they provide a housing for the cutting knife and a notch

for holding a match stem. Moreover, the present invention is more efficient in operation, costs less to manufacture, is neater in appearance, and takes up less space in the 60 pocket, than my previous one.

Referring to the accompanying drawings, the numeral 1 is used to indicate the open end cover or casing almost universally employed to incase an open top match box as 65 2, while the numeral 3 indicates matches retained in the box.

The parallel sides 10 of the holder are connected in the rear by the connecting side 20. At their top ends, the parallel 70 sides 10 are preferably provided with portions or extensions as 11 which are fashioned in detail as illustrated in Fig. 3. In order to fit the match box snugly and also in order to provide an even slideway bottom for 75 a compartment or housing, these extensions are arranged in the same plane at right angles to the parallel sides 10. To provide a suitable slideway bottom for the housing, the inner edges of these extensions meet for 80 a short distance intermediate their lengths. The front inner edges of these extensions do not meet, but a portion of each is cut away or prepared to provide the single 85 notch or recess 15, the widest part of which notch faces the open front side of the holder. The office of notch 15 is to receive and to retain the stem of an ignited match as illustrated in Fig. 1. The rear inner portions of extensions 11 are made so as to provide 90 a large single opening 14, which communicates in part with the superimposed aperture 22 in order to provide a continuous hole for the reception of a tip end of a cigar. For a considerable distance the opposite inner edges of the opening 14 are parallel to 95 provide guides or bases for the slidable knife 30. On the lower front edges of the parallel sides 10, extensions as 13 are employed to serve as guide-retainers for the match box 1. The top end of connecting side 20 is also preferably provided with an extension as 21, which extension, under this construction, is prepared with a longitudinal slot or guide in its underneath side in 100 order that it may complete the compartment or housing for the slidable knife 30, when secured to extensions 11. At its front end, extension 21 is provided with projecting lugs as 23 and 24. Lugs 23 are designed 105 to penetrate eyelet holes as 12, which are provided for the purpose in extensions 11.

95

100

105

110

After penetrating the eyelet holes, these lugs are bent against the underneath surface of extensions 11 thereby securing extension 21 with extensions 11. In its rear end, extension 21 is provided with aperture 22 which communicates with opening 14 and also with the longitudinal chamber in the knife housing.

The knife 30 has a cutting edge 31 on one end and a thumb piece 32 on the other end, while adjacent the thumb piece, it is provided with a longitudinal slot 33. When the knife is arranged in its housing, the lug 24 is inserted in slot 33 thereby preventing the knife from being withdrawn from its housing when moved to its forward position as shown in Fig. 3. Thus the cutting knife is slidably secured in its housing, and is adapted to be drawn forward to permit the tip of a cigar to be entered in aperture 22 and to be pushed backward to cut off the entered tip.

Obviously, the match box is entered through the open bottom end of the holder, and then advanced until it occupies the position illustrated in Fig. 2. When the match box is partly withdrawn as shown in Fig. 1, a protected air chamber is provided in the top of the holder. If it is desired to light a cigar in the open when the wind is blowing or in any place where there are air currents, the stem of an ignited match is placed in notch 15 so that the flame is held in the protected air chamber thereby safeguarding the flame from being extinguished by the outside air influences.

While I prefer to make my invention in the form as above described, the connecting side may be prepared to provide the bottom portion of the head end, while the other extensions or even one of them may be fashioned to make the top or counter portion; or, on the other hand, the head end with its respective features may be made separately and then secured on the top ends of the sides. Various changes, therefore, in the details of the construction of the head end may be resorted to, provided the principles of construction set forth respectively in the appended claims are employed.

I claim:

1. A device of the character described comprising a box form having two parallel sides and a connecting side, an in-bent extension on the top end of each of the parallel sides to form a portion of a head including a housing and an opening, an in-bent extension on the top end of the connecting side to complete the head portion including the housing and opening, a knife slidably arranged in the housing thus formed and adapted to be reciprocated so that its cutting edge passes said opening.

2. A device of the character described comprising a box form having two parallel

sides and a connecting side, in-bent extensions on an end of the parallel sides to provide a portion of a head including a housing, an in-bent extension on an end of the connecting side to complete the head portion including the housing, a transverse opening in the completed head portion in communication with the housing, and a cutting knife slidably arranged in said housing and adapted to be reciprocated past said opening whereby to cut off the tip of a cigar.

3. A device of the character described comprising a box form having two parallel sides and a connecting side, in-bent extensions on an end of the parallel sides to form a head portion and to provide a notch adapted to receive and retain a match stem, an in-bent extension on an end of the connecting side adapted to be united with the aforesaid extensions to provide a housing, a transverse opening in the head portion in communication with the housing, and a knife slidably secured in said housing, which knife is adapted to be operated so that its cutting edge is reciprocated past said opening.

4. A device of the character described comprising a single sheet of material bent to form two parallel sides and a connecting side, an in-bent portion on the same end of each of the sides which portions are adapted to be united to form a head portion including a longitudinal compartment, a transverse aperture in the head portion in communication with said compartment, a notch in the free end of the head portion and adapted to receive and retain a match stem, and a knife arranged in said longitudinal compartment which knife is adapted to be slidably moved to reciprocate its cutting edge past the said aperture.

5. A device of the character described comprising a box form having two parallel sides and a connecting side, portions in-bent at right-angles on an end of the parallel sides and having their inner edges meeting, said in-bent portions being designed to form together a single opening in their rear ends and a single notch in their front ends, a portion in-bent at right-angles on an end of the connecting side and having a transverse aperture designed to communicate with the single opening and an inverted channel in communication with said aperture, means on the latter in-bent portion for securing it to the former in-bent portions, and a knife slidably arranged in said channel between the former and latter in-bent portions and adapted to have its cutting edge reciprocated past the said aperture.

6. A device of the character described comprising a single sheet of material bent to form a connecting side uniting at right-angles with two parallel sides, an in-bent

- portion carried on the top of each parallel side to form a portion of a head end, an opening in the head portion thus formed adjacent the said connecting side, a V-shaped notch adapted to receive and retain a match stem in the opposite or free end of said head portion, eyelet holes in said head portion, an in-bent portion carried by the top end of said connecting side and having 5 a circular aperture in communication with the aforesaid opening and forming a housing, a knife slidably arranged in said housing and adapted to be reciprocated so that its cutting edge passes said circular aperture whereby to cut off the end of a cigar, and lug means carried by said in-bent end portion and adapted to engage the eyelet 10 holes in said head portion as set forth.
- 15 7. A device of the character described comprising a box form having two parallel sides and a connecting side, each parallel side having an in-bent extension on the top 20
- end thereof, and a plate connected to said in-bent extensions, said plate having an opening, and a knife slidably arranged between 25 said plate and the in-bent extensions.
8. A device of the character described comprising a box form having two parallel sides and a connecting side, each parallel side having an in-bent extension at the top 30 end thereof, the said in-bent ends providing a slot therebetween adapted to hold a match, and a plate connected to said extensions, said plate having an opening, and a knife slidably arranged between the in-bent ends 35 and plate as set forth.

In testimony whereof I have signed my name to this specification in the presence of two subscribing witnesses.

GEORGE E. VAN DUSEN.
